COMBINED TELEVISION RECEIVER AND TELEPHONE

Edward L. Byer, Fort Wayne, Ind., and John Cuccio, Westport, Conn., assignors to International Telephone and Telegraph Corporation, Nutley, N.J., a corporation of Maryland

Filed Feb. 6, 1964, Ser. No. 78,540

Term of patent 14 years

(Cl. D56—4)

Fig. 1

The dominant features of our new design reside in the portions shown in solid lines.

We claim:

The ornamental design for a combined television receiver and telephone, as shown and described.
